SPRAYER

Ivar Jepson, Chicago, Ill., assignor to Chicago
Flexible Shaft Company, Chicago, Ill., a cor-
poration of Illinois

Application December 16, 1936, Serial No. 116,082

9 Claims. (Cl. 299—96)

This invention relates to spraying devices and has special reference to a portable liquid sprayer of novel characteristics.

An important object of the invention is the provision of a hand sprayer having improved structural characteristics directed to economy in manufacture and dependability and convenience in use.

Another object of the invention is the provision of a device of the character described having improved means for filling and refilling the same.

A still further object of the invention is the provision of a sprayer having improved valve structure.

Another aim of the invention is the provision of a sprayer having an improved pump for developing spraying pressure on the liquid.

Other objects and advantages will become apparent from the following description and the accompanying drawing, in which—

Figure 1 is a vertical section through a sprayer embodying my invention;

Fig. 2 is a section on the line 2—2 of Figure 1;

Fig. 3 is a section on the line 3—3 of Figure 1;

Fig. 4 is an enlarged longitudinal section through the lower end of the pump;

Fig. 5 is a section on the line 5—5 of Figure 1, and

Fig. 6 is a section on the line 6—6 of Fig. 4.

The embodiment of the invention herein shown is intended primarily for the purpose of spraying clothes to dampen the same prior to ironing, but it will be understood that the invention is by no means limited to this particular application and the features thereof may be embodied in spraying devices for numerous purposes. This embodiment includes a vessel having side walls 7, in this instance of cylindrical cross-section tapering inwardly from bottom to top as shown in Figure 1, a bottom 8, and an open top 9. The side walls are constricted adjacent the open top to provide a threaded neck portion 11 and a transverse annular ring 12 for a purpose presently to be described. The vessel is in this instance formed of sheet metal and the bottom 8 is inserted into the bottom end of the cylindrical side walls 7 and welded or otherwise affixed thereto as shown at 13 so as to be water and air tight. The bottom 8 slopes upward toward the longitudinal center line of the vessel in the manner of a cone and has an upwardly extending cylindrical flange 14 at the center screw threaded on its inner surface for the reception of the threaded end 15 of a plug or closure designated generally

by the numeral 16. The bottom 8 also has small openings 17 and 18 adjacent the flange 14. The plug 16 has a cone-shaped face 19 complementary to the curvature of the bottom 8 adapted for the reception of a gasket 21 in such manner that when the plug 16 is screwed into the flange 14 by means of a wing 22, the portion 19 will press the gasket 21 firmly against the bottom closing the openings 17 and 18 as well as the main opening defined by the flange 14.

The neck portion 11 is threaded on its outer surface for the reception of a body portion designated generally by the numeral 23 which is threaded thereon and seats against the annular shoulder 12, a gasket 24 being seated therebetween to seal the junction between the parts. The body member 23 is preferably formed as a casting with the outer surface thereof conforming substantially with the shape characteristics of the side walls 7 with the exception of a nozzle support 25 and a handle designated generally by the numeral 26. A feature of the invention lies in the provision of a cast body member as shown in Figure 1 upon which the remainder of the sprayer is assembled in such manner as to materially simplify and reduce the cost of construction and at the same time to enhance the efficiency thereof.

The body member 23 has a centrally disposed bore within which a pump cylinder 27 has a press fit, the cylinder projecting slightly beyond the upper side of the body as shown at 28 and being screw threaded on its outer surface for the reception of a cap 29 which abuts against the upper end of the body and acts as a closure for the pump cylinder, the cap having openings 31 for the passage of air into the cylinder. The body has a channel 32 extending through the nozzle support 25 and communicating with an annular recess 33 of the central bore. A channel 34 connects the annular recess to a laterally disposed bore 35 into which also terminates a bore 36 extending to the interior of the vessel, the bore 36 being extended downward by a pipe 37 which has a press fit in the lower surface of the body member and terminates adjacent the junction of the side walls 7 and bottom 8 on the side of the vessel beneath the nozzle support 25. The lower end of the pipe 37 has a cup-like flange 38 arranged to support a fine screen 39 (Fig. 3) to prevent the passage of large particles of solids into the pipe. The bore 35 provides a valve chamber opening into a recess 41 in the handle and has a sleeve 42 threaded therein which serves to confine and clamp a valve diaphragm 43 at its edges. The diaphragm 43 may be made of any

resilient or flexible material suitable for the purpose herein disclosed, though I prefer to use rubberized canvas or one of the various forms of composition packing, a suitable form being "Garlock" 5 No. 7561 packing. An annular recess 44 is formed in the end of the bore 35 to provide an annular shoulder 45 for the purpose of retaining the diaphragm at its annulus, a washer 46 being positioned between the end of the sleeve 42 and the 10 packing for this purpose. The recess 44 also provides an upraised shoulder 47 around the bore 34 for sealing contact of the diaphragm 43. A pin 48 is slidably positioned within the sleeve 42 with its inner end positioned to bear against the 15 diaphragm in such manner that when forced inward to the extremity of its movement the end of the pin urges the diaphragm against the shoulders 47 so as to prevent the flow of liquid between the channels 34 and 36. The outer end of the 20 pin 48 is recessed as shown at 49 for the reception of the slotted end 51 of a lever designated generally by the numeral 52. The end of the lever has a slot 53 within which the portion of the pin 48 of reduced diameter is receivable so that upon 25 tilting movement of the lever the end thereof will abut against either side of the slot 49 so as to urge the pin 48 inward or outward. The lever 52 is rotatably carried on a pin 54 which is positioned in the sides of the recess 41 through ears 30 55, the pin 54 being positioned therein at a point below the longitudinal center line of the pin 48 so that when the right hand end of the lever 52 facing Figure 1 is urged upward by means of a spring 56, the pin 48 is urged inward to prevent 35 the flow of liquid between the channels, and when the lever is manually depressed by the thumb of the operator against the tension of the spring 56, the pin 48 is drawn outward permitting liquid to flow from the channel 36 to the channel 34 and 40 thence through the channel 32 to the nozzle.

The nozzle is formed by a member 57 having a bore 58 and threaded onto the nozzle support 25 as shown at 59, the bore 58 terminating in an orifice 61. Within the bore 58 which communicates with the channel 32 is a spray tip 62 comprising a cylinder loosely received in the bore 58 and having a plurality of helical grooves 63 on its outer surface for the passage of fluid to impart suitable directional characteristics thereto.

50 Positioned within the pump cylinder 27 is a plunger mechanism including a plunger rod 64 having a knob 65 attached to the upper end thereof and adapted to be reciprocated from above the body member for the purpose of pumping a small amount of air into the vessel and thus placing a pressure upon the liquid therein. A coiled spring 66 is positioned on the rod 64 in a position to cushion the movement of the plunger at the upper end of its stroke. Adjacent the lower end 60 of the rod 64 is an annular collar 67 (Fig. 4) fixed to the plunger and a gasket 68 which bears against the lower side of the collar, the plunger being slightly reduced in diameter at this point to provide a shoulder 69. A plunger head 71 is positioned on the rod below the gasket 68 and has a bore 72 somewhat larger than the rod for the passage of air on the junction therebetween. The body is retained thereon by means of a nut 73 at the lower end of the rod. The piston head carries the usual sealing leather 74 retained on the head by means of a washer 75 which is in turn held in position by an upset portion 76 on the head. When the plunger rod 64 is reciprocated, the nut 73 serves to draw the plunger head upward upon the upward movement of the rod per-

mitting air to pass from the upper end of the cylinder to the lower end. Upon the initial downward movement of the plunger rod the gasket 68 comes into contact with the upset portion 76 by movement of the rod through the head thereby cutting off communication between the upper and lower ends of the cylinder so that the air in the cylinder below the plunger head is compressed.

10 The lower end of the pump cylinder 27 carries a transverse wall 77 having a centrally disposed opening 78 within which is positioned a pin 79 having heads 81 and 82 on opposite ends thereof. The head 82 carries a gasket 83 adapted to bear against the lower side of the end 77 so as to cover the opening 78, and a spring spider 84 acts between the bottom 77 and the head 81 to normally urge the valve formed by these elements into the closed position as shown in Fig. 4. It will be seen that upon downward movement of the plunger and the associated compression of air in the lower part of the cylinder, the valve will be forced open by the increase of pressure against the tension of the spring 84, thereby allowing passage of air out of the pump cylinder into the vessel. It will further be observed that the opening 78 will be closed immediately upon the reduction of pressure within the cylinder to a predetermined point, thus preventing the entrance of liquid into the cylinder from the vessel.

20 In operation, the sprayer is inverted, the plug 16 removed and liquid is introduced into the vessel until filled to the level of the openings 17 and 18. During this operation the central threaded opening defined by the flange 14 and the holes 17 and 18 cooperate functionally in that the liquid passes in through the central opening and air out through the openings 17 and 18. These holes also serve an additional function in defining the proper maximum level of liquid in 30 the container and cooperate with the sloping bottom wall 8 in retaining a sufficient amount of air space in the vessel to permit of the proper application of pressure thereto. When filled, the plug 16 is re-inserted and tightened, 40 the sprayer is placed on its base and the handle 65 is reciprocated, causing air to be drawn through the openings 31, pass through the pump cylinder and through the valve opening 78 at the bottom thereof into the vessel, thus generating a sufficient head of air pressure at the top of the vessel. With the sprayer in this condition, depression of the lever 72 by the thumb of the operator's hand in which the sprayer is carried serves to withdraw the pin 48, whereby the pressure of liquid passing upward through the tube 37 and the channel 36 causes the diaphragm to be moved away from the end of the channel 34 so that the liquid may flow from the channel 36 to the channel 34, thence through the annular 50 recess 33, the channel 32 and out through the orifice 61 from which it emerges under considerable pressure causing a very fine spray or mist. When the lever 52 is released, the flow of liquid ceases by action of the pin 48 forcing the diaphragm against the shoulder 47.

55 Attention is directed to the simplicity of construction which makes it possible to manufacture the sprayer at very small cost. The entire mechanism is carried on a cast metal body portion 23 which is bored to provide suitable channels, the nozzle support 25 and handle 26 being cast integral and forming a part of the body member. By this means the operating parts including the pump and the diaphragm valve may be assem- 60 70 75

bled as a unit, and thereafter the vessel suspended from the body member. The pump is positioned in the center of the body member and passes therethrough so as to provide a long stroke on the pump which extends through a greater portion of the height of the sprayer. It will be observed that the top of the body is recessed to provide for receiving the operating lever and also for providing access to the chamber in which the movable valve member is mounted. Thus, the valve member, as well as the removable means for retaining it, is easily accessible for installation and replacement through the recessed side of the body. The parts are so relatively arranged that the finger operated lever advantageously coordinates the handle and the valve structure, making for simplicity in construction and greater convenience in use.

Attention is also directed to the diaphragm valve structure which provides a simple, cheap and durable valve arrangement, the diaphragm being positively actuated into a closing position by operation of the lever 52 and being moved to the open position by the pressure on the liquid.

Attention is further directed to the construction of the pump plunger, particularly in the arrangement between the rod and the head wherein the rod moves a short distance with respect to the head at the end of the stroke. Through this arrangement the plunger may be moved to its lowermost position so that the knob 65 contacts the upper surface of the cap 29 while pressure is present in the vessel. It will be understood that when the pump is operated to raise the pressure of the vessel there will always be remaining at the last downstroke of the plunger a small amount of air in the lower end of the cylinder which is under relatively high pressure so that when the knob 65 is released the plunger will be urged upward under the expansion of the residual air. With the present construction the plunger may be moved to its lower position by simply rotating the knob 65 while applying a very light pressure, which operation permits the air in the lower end of the cylinder to move upward along the rod through the bore 72 and past the packing 68.

While I have thus described and illustrated a specific embodiment of the invention I am aware that numerous alterations and changes may be made therein within the spirit of the invention and I do not wish to be limited except as required by the prior art and the scope of the appended claims in which

55 I claim:

1. The combination in a sprayer for discharging a liquid under pressure, of a one-piece cast body having inlet and outlet channels for conducting liquid therethrough, a valve chamber intersecting therewith and having an annular shoulder surrounding the end of one of said channels, a flexible diaphragm confined at its peripheral edges and arranged to move in the center portion thereof between a position against said shoulder to prevent communication between said channels and a position permitting communication therebetween, and a manually movable pin arranged to move between a position to urge said diaphragm against said shoulder and a retracted position, for movement of said diaphragm under the fluid pressure to control the discharge of liquid, the top of the body being recessed to provide for operation of the lever therein and to provide for access to the valve

chamber on installation and replacement of the diaphragm.

2. The combination in a sprayer of a vessel having a screw-threaded upper end and an open top, a one-piece cast metal body member having a handle projecting laterally and downwardly from one side, a nozzle at the opposed side and an intermediate portion shaped for reception of the upper end of said vessel to support the same in depending relationship and close the top of said vessel, a pump cylinder carried on and depending from said last-mentioned portion axially in said vessel, a pump plunger in said cylinder extending through said intermediate portion and projecting thereabove for manual reciprocation to pump air into said vessel, a tube within the vessel depending from said intermediate portion and extending to a point adjacent the bottom thereof, said body having a channel extending from said tube to said nozzle to conduct liquid from the bottom of the vessel to the nozzle, valve means intermediate the ends of said channel including a movable valve member for controlling the flow through said channel, and a finger operable lever having engagement with the valve member for imparting movement thereto, the top of the body being recessed to provide for operation of the lever therein and to provide communication with the valve means for installation and removal of the valve member.

3. A liquid sprayer comprising in combination a channeled and recessed cast body having a handle extending from one side thereof for manipulation of the sprayer, a nozzle extending from the opposite side thereof, a centrally disposed pump supporting bore, converging inlet and outlet channels, the outlet channel communicating with said nozzle, a valve chamber at the convergence of said inlet and outlet channels, an annular bottom recess for the reception of a vessel and a top recess extending radially of the body for the reception of a lever, a vessel for holding fluid seating in said bottom recess, a pump seated in said pump supporting bore reciprocable from above said body, conduit means extending from said inlet channel to a low point in said vessel for conducting liquid therefrom under pressure developed by said pump, a flexible diaphragm confined at its peripheral edge in the valve chamber and movable at its center between a position closing communication between said bores and a position permitting communication, the valve chamber opening into the top recess so that the diaphragm may be installed and replaced through the recess, a thumb actuated valve lever positioned and articulated in said top recess to move between a position to urge said diaphragm to the closed position and a retracted position for movement of said diaphragm under the fluid pressure, and spring means acting between said body and said lever for urging the lever to the closed position against the fluid pressure.

4. The combination in a liquid sprayer of a one-piece cast body member having a centrally disposed portion, a handle extending outwardly and downwardly from one side thereof for manipulation of the sprayer, a nozzle support at the opposite side thereof, a centrally disposed pump supporting bore in said central portion opening through the body for the passage of a pump element, an annular bottom recess concentric with said bore for the reception of a liquid container, the body being recessed at its top with part of the recessing in said handle for the reception

of valve actuating means, converging inlet and outlet channels, the outlet channel communicating with said nozzle, a chamber at the point of convergence of said channel shaped to receive a 5 diaphragm in a position to block communication between said channels upon mechanical distortion thereof to control the flow of liquid through the channels, the chamber being accessible through the top recessing for installation and 10 removal of the diaphragm.

5. In a liquid sprayer, an open top liquid container, a body serving as the cover for the container, the body being channeled and recessed in a plane transverse to the longitudinal axis of 15 the sprayer to provide a nozzle channel and a lever recess in alignment diametrically of the sprayer, a spray nozzle at the outer end of the nozzle channel, the lever recess being open at the top of the body, the body extending outwardly 20 and downwardly from the recessed portion to provide a handle, valve means in the body to provide communication between the container and the nozzle channel including a movable valve member, said valve member being accessible 25 through the lever recess for installation and replacement, and a lever in said recess having operative engagement with the valve member for imparting movement thereto.

6. In a liquid sprayer, an open top liquid 30 containing vessel, a body forming a cover closing the top of the vessel, a pump cylinder depending from the body into the vessel, pump mechanism associated with the cylinder including a plunger in the cylinder reciprocable for pumping small 35 amounts of air into the vessel and thus placing a pressure upon the liquid therein, an inlet tube depending from the body to a lower point in the vessel, the body having a handle depending from one side and a spray nozzle at the opposite side, 40 a valve chamber in the body having an inlet communicating with said inlet tube and an outlet communicating with the spray nozzle, a flexible diaphragm valve in the valve chamber confined 45 at its peripheral edge and movable at its center to close and open said communication, removable means clamping the peripheral edge of the diaphragm in fixed position in the valve chamber, the top of the body member being recessed 50 to provide for the reception of a lever and to provide access to the valve chamber for installation and replacement of the diaphragm and its clamping means, and a lever disposed in said recess and having operative engagement with the diaphragm 55 for imparting movement thereto.

55. 7. In a liquid sprayer, an open top liquid containing vessel, a body serving as a cover for the vessel, a pump on the body operable for placing pressure on the liquid within the vessel, the body being interiorly channeled to provide a nozzle 60 channel in a diametrical plane, a spray nozzle at the outer end of said channel, a valve chamber in the body at the inner end of said channel, an inlet tube communicating at its upper end with 65 said valve chamber and extending to a lower point in the vessel, a valve member in said valve chamber movable for opening and closing communication between said inlet tube and said nozzle channel, and a finger operable lever for moving 70 said valve member, the body having a handle in said diametrical plane at the side opposite from

the spray nozzle, the top of the body being recessed in said plane to provide access to said valve chamber for installation and replacement of said valve member and to receive the finger lever.

8. In a liquid sprayer, an open top liquid containing vessel, a cast body forming a cover closing the top of the vessel, a pump cylinder depending from the body into the vessel, pump mechanism associated with the cylinder including a plunger in the cylinder reciprocable for pumping small 10 amounts of air into the vessel and thus placing a pressure upon the liquid therein, an inlet tube depending from the body to a lower point in the vessel, a radially extending nozzle 15 channel, a spray nozzle on the body at the outer extremity of said channel, a valve chamber in the body having an inlet communicating with said inlet tube and an outlet communicating with said nozzle channel, a movable valve member in said chamber for closing and opening communication 20 between said inlet and said outlet, a handle depending from the body at the side opposite from the nozzle, the top of the body being recessed to provide access to the valve chamber and to provide for reception of a valve operating member, 25 said valve chamber being accessible through the open top of the body for installation and replacement of said valve member, and a valve operating member in the recessed top portion having operative engagement with the valve member for imparting movement thereto and substantially closing 30 the recessed portion.

9. In a liquid sprayer, an open top liquid containing vessel, a one-piece cast body forming a cover closing the top of the vessel, a pump cylinder fixed at its upper end in the body and depending into the vessel, pump mechanism associated with the cylinder including a plunger in the cylinder extending through and above the cover body and reciprocable by means of its upper end 40 for pumping small amounts of air into the vessel and thus placing a pressure upon the liquid therein, an inlet tube depending from the body to a lower point in the vessel, the body being channeled and recessed to provide a nozzle channel 45 and a lever recess in a plane disposed diametrically of the sprayer, the recessed portion of the body being extended to provide a handle, a spray nozzle on the body at the outer extremity of said channel, the body having a valve chamber 50 in said diametrical plane providing communication between said inlet tube and said nozzle channel, a flexible diaphragm in said chamber movable to close and open said communication between the inlet tube and the nozzle channel, 55 the valve chamber being accessible through said lever recess for installation and replacement of the diaphragm, and a lever in said recess having operative engagement with the diaphragm, the lever being spring pressed in one direction to move the diaphragm to normally close said communication and being operable by finger pressure to release said spring pressure, the diaphragm 60 when so released being unseated by the pressure in the vessel so that the liquid under pressure in the vessel will be communicated through the tube, valve chamber and nozzle channel to the spray nozzle.
